UNITED STATES PATENT OFFICE.

ALPHONSE C. KETTERER AND GEORGE P. SLANKER, OF SANTA BARBARA, CALIFORNIA, ASSIGNEES OF ONE-TENTH TO JOSEPH A. ALLARD, JR., OF POMONA, CALIFORNIA.

COIN CLOCK BANK.

Application filed August 16, 1922. Serial No. 582,192.

To all whom it may concern:

Be it known that we, ALPHONSE C. KETTERER and GEORGE P. SLANKER, citizens of the United States, residing at Santa Barbara, in the county of Santa Barbara, State of California, have invented a new and useful Coin Clock Bank, of which the following is a specification.

Broadly considered, it is the object of this invention to promote thrift, by constraining a person to deposit a coin, whenever a clock is wound, it being impossible to wind the clock until a coin is deposited.

It is contemplated that the winding shaft of the clock shall be shielded by a guard, to the end that the winding key cannot be placed upon the shaft until the guard is released, and, specifically, the invention aims to provide novel coin-controlled means for releasing the guard, means being provided for resetting the guard with respect to the winding shaft.

Another object of the invention is to provide novel means carried by the winding shaft, whereby the guard may be reset, said means being so constructed that it will in no wise interfere with the winding of the clock or impede the rotation of the winding shaft, as the clock runs down.

It is within the province of the disclosure to improve generally and to enhance the utility of devices of that type to which the invention appertains.

With the above and other objects in view, which will appear as the description proceeds, the invention resides in the combination and arrangement of parts and in the details of construction hereinafter described and claimed, it being understood that, within the scope of what is claimed, changes in the precise embodiment of the invention shown can be made without departing from the spirit of the invention.

In the accompanying drawings:—Figure 1 shows in rear elevation, a device constructed in accordance with the invention; Figure 2 is a vertical section, wherein parts appear in elevation; Figure 3 is a section on the line 3—3 of Figure 2, the line 2—2 in Figure 3 indicating the cutting plane on which Figure 2 is taken; Figure 4 is a fragmental horizontal section taken through a portion of the casing, the coin chute, and attendant parts; Figure 5 is a vertical sec-

tion disclosing the mounting of the arm 55 which carries the dog.

In carrying out the invention, there is supplied a case or support 1, provided at its lower end with a money receptacle 2, which may be in the form of a drawer, held closed by a lock 3. It is obvious that the taste of the public with regard to ornamentation, the desire for compactness, and other considerations, will dictate the form of the case, the specific case, money receptacle and lock, shown in the drawings being illustrative merely, and not mandatory. A coin chute 4 is mounted on the rear wall of the case 1 and discharges into the receptacle 2, the chute opening through the top 70 of the case, if desired. A clock casing 5 is held by clamp brackets 6, or otherwise, on the forward wall of the support 1. The mechanism within the clock casing 5 may be constructed as desired, but it is preferred 75 that this mechanism be of such a nature that the clock must be wound frequently, since it is proposed that a coin must be deposited each time that the clock is wound, the amount of money saved being increased, 80 by the depositing of each coin. It is therefore suggested that the device be used in connection with a twenty-four hour clock, comprising a winding shaft 7, a setting arbor 8, and a regulator 9, the back of the 85 case 1 having a slot 10, giving access to the regulator 9, the winding shaft 7 being accessible through an opening 11 in the case 1, the case having an opening 12 whereby a key may be placed upon the setting 90 arbor 8.

Comparing Figures 3 and 5, it will be observed that the winding shaft 7 has a fixed disk-like shoulder 14. A compression spring 16 bears at its inner end against the shoulder 14 and surrounds the squared portion of the shaft 7, the outer end of the spring 16 bearing against the upper end of an angular spring strip 15, slidable on the squared portion of the shaft 7 and secured 95 at its lower end to the clock casing 5, the strip 15 constituting a key-ejector for the shaft 7, as will be explained hereinafter.

An arm 17 is mounted for vertical swinging movement on the winding shaft 7, to 100 the rear of the shoulder 14. The arm 17, however, is held frictionally on the winding shaft 7, so that when the winding shaft is

rotated, the arm may swing. With this end in view, a compression spring 19 surrounds the inner portion of the winding shaft 7, one end of the spring abutting 5 against the clock casing 5, and the other end of the spring abutting against a washer 18 on the winding shaft, the washer engaging the arm 17 and pressing the arm against the shoulder 14, under the impulse 10 of the spring 19, the arm thus being held frictionally on the shaft 7, for movement with the shaft. Stops 20 and 21 project rearwardly from the clock casing 5. The stops 20 and 21 engage the arm 17 and 15 hold the arm, thereby permitting the winding shaft 7 to rotate in the arm, under conditions which will be set forth when the operation of the device is explained.

The numeral 22 marks a dog, mounted to 20 swing parallel to the arm 17, on a pivot element 23 carried by the arm. A spring 25 is mounted on the pivot element 23 and engages a projection 24 on the dog, to swing the dog with respect to the arm 17, the projection 24, however, being adapted to co-operate with the arm, to limit the swinging movement of the dog responsive to the spring 25. The dog 22 is provided with a convexed outer edge 26 and with a concaved 30 inner edge 58.

A vertical guide 27 is supported on the rear wall of the case 1, and within the guide, a disk-like guard 28 is movable, the guard having an opening 29 adapted to be brought 35 into and out of registration with the opening 12 in the rear wall of the case 1. The guard 28 has an upstanding arm 30 carrying a forwardly presented finger 31 where-with the dog 22 is adapted to cooperate. 40 The guard 28 includes a bell crank lever 32, fulcrumed at 33 on the rear wall of the case 1 for vertical swinging movement, swinging movement of the bell crank lever in the direction of the arrow A in Figure 1 being limited by a stop 34 on the rear wall 45 of the case 1. The upstanding arm of the bell crank lever 32 is supplied with a forwardly projecting detent 43.

The numeral 35 designates an angular 50 latch, including arms 36 and 37, the arm 36 being adapted to cooperate with the detent 43 on the bell crank lever 32, and the arm 37 carrying a lateral projection 39 received in a transverse slot 40 formed in the inner edge 55 of the coin chute 4. The latch 35 is carried by a fulcrum element 38 mounted in the coin chute 4. A weak spring 41 is anchored at one end on the coin chute 4 and is engaged about the fulcrum element 38, the spring 60 coacting with the arm 36 of the latch 35, to hold the latch in the position delineated in Figure 2 of the drawings.

When the parts are arranged as shown 65 in Figure 2, the projection 39 on the arm 37 of the latch 35 is located in the slot 40 of

the coin chute 4 and is held there yieldingly by the action of the weak spring 41 upon the arm 36 of the latch. The upper end of the bell crank lever 32 abuts against the stop 34, and the detent 43 on the bell 70 crank lever engages the end of the arm 36 of the latch 35. The shutter or guard 28 on the bell crank lever 32 thus is held positively but releasably in such a position that the opening 29 in the guard does not coincide with the opening 12 in the case 1, it being impossible to apply a key to the arbor 8 and set the hands of the clock. Further, the guard 28 is interposed between the shaft 7 and the opening 11 in the rear wall of the case 1, and, consequently, an operator cannot apply a key to the shaft 7 and wind the clock. If a coin 50 be deposited in the chute 4, the coin will pass downwardly through the chute into the receptacle 2. The coin 50, moving downwardly in the coin chute 4, strikes the projection 39 on the arm 37 of the latch 35 and tilts the latch on its fulcrum 38, the weak spring 41 being overcome, the arm 36 of the latch being raised out of engagement with the detent 43 on the bell crank lever 32, and the bell crank lever being set free. The guard 28 acts as a weight, and causes the bell crank lever 32 to swing on its fulcrum 33 until the opening 29 in the guard is brought into coincidence with the opening 12 in the case 1, whereupon a key may be applied to the setting arbor 8. When the guard 28 moves downwardly, the winding shaft 7 is uncovered, and the operator may apply a key to the shaft, to wind the clock. When the guard 28 moves downwardly, to expose the shaft 7 and the arbor 8, the arm 30 and the finger 31, which form part of the guard, are carried downwardly, until the finger 31 is located in the path of the dog 22. When the winding shaft 7 is rotated, the arm 17 and the dog 22 move with the shaft in a counterclock-wise direction (Figure 2), the concaved inner edge 58 of the dog riding over the finger 31 on the arm 30 of the guard 28, and the dog swinging upwardly on its pivotal mounting 23, the spring 25 being put under tension. As soon as the point 115 of the dog 22 has passed the finger 31, the dog swings downwardly under the effect of the spring 25, until the projection 24 on the dog engages the arm 17 and stops the downwardly swinging movement of the dog. The dog 22 then is so positioned that, when the arm 17 and the dog swing clock-wise 120 (Figure 1), under conditions to be explained hereinafter, the convexed outer edge 26 of the dog will cooperate with the finger 31 of the guard 28. The arm 17, moving in a counterclock-wise direction with the winding shaft 7 (Figure 2), ultimately comes into engagement with the stop 20, but the operator may con- 125 130

tinue to rotate the shaft 7, and to wind the clock, because the arm 17 is connected to the shaft 7 with a frictional hold, the spring 19 (Figure 3) pressing the arm against the 5 shoulder 14 on the shaft 7.

When the pressure in an inward direction on the winding key is relieved, the key is carried outwardly off the shaft 7, by the spring key-ejector 15 assisted by the spring 10 16 (Figure 3).

As the clock starts to run down (Figure 1), the shaft 7 rotates clock-wise, the arm 17 and the dog 22 moving clock-wise until the 15 arm engages the stop 21. Thereafter, the shaft 7 rotates in the arm 17, the arm being frictionally held upon the shaft. The point of the dog 22 passes beneath the finger 31 on the guard 28, and the convexed outer edge 26 of the dog cooperates with the finger to 20 raise the guard, until the opening 29 in the guard no longer registers with the opening 12 in the case 1, and until the guard is interposed between the squared end of the winding shaft 7 and the opening 11 in the 25 rear wall of the case 1, it being impossible then to wind or set the clock.

When the guard 28 is raised, as aforesaid, the bell crank lever 32 is swung on its fulcrum 33, the upstanding member of the bell 30 crank lever moving in the direction of the arrow A in Figure 1, until the upper end of the said member cooperates with the stop 34. As the detent 43 moves in the direction of the arrow A in Figure 1, the detent rides 35 along a portion of the lower edge of the arm 36 of the latch 35, tilts the latch on its fulcrum 38 and engages behind the end of the arm 36, as depicted in Figure 2, the parts being restored to the positions shown 40 in that figure, thus to remain until another coin 50 is inserted into the coin chute 4 and the clock rewound.

In Figure 2, the coin 50 is shown as filling the coin slot 4 transversely. The machine, 45 however, may be operated by means of a smaller coin, simply by inclining the casing with respect to the vertical, in the direction indicated by the arrows B in Figure 2, and permitting the smaller coin to roll along 50 the inner edge of the coin slot 4, over the projection 39 on the arm 37 of the latch 35.

What is claimed is:—

1. A clock comprising a winding shaft; a movable guard for the winding shaft; a coin 55 chute; a movable latch extended into the chute and cooperating with a portion of the guard to hold the guard set with

respect to the shaft; an arm frictionally held on the shaft to swing when the shaft is rotated in opposite directions; means 60 for stopping the arm to permit the shaft to rotate therein; a dog pivoted to the arm and slideable freely over a part of the guard when the shaft is rotated in one direction to wind the clock, the dog engaging said part 65 of the guard to move the guard to set position with respect to the shaft and to engage the guard with the latch when the shaft rotates in a reverse direction as the clock runs down.

2. A clock comprising a winding shaft; a movable guard for the winding shaft; coin-controlled means for releasing the guard from set position with respect to the winding shaft; a resetting device cooperating with 70 the guard, and means for stopping the movement of the resetting device, the resetting device being frictionally carried by the shaft, whereby the shaft may be rotated independently of the resetting device to wind 75 the clock, and whereby the shaft may rotate independently of the resetting device as the clock runs down, when the movement of the resetting device is stopped by the last-specified means.

3. A clock comprising a winding shaft; a movable guard for the winding shaft; coin-controlled means for releasing the guard with respect to the winding shaft; and a 80 resetting device for the guard, the resetting device embodying an arm frictionally held on the shaft, a dog pivoted to the arm and movable freely over a part of the guard when the shaft is rotated to wind the clock. 85 the dog cooperating with said part of the guard to reset the guard with respect to the shaft as the clock runs down.

4. Mechanism of the class described, constructed as set forth in claim 3, and further characterized by the fact that the dog is provided with a projection which, cooperating with the arm, limits the movement of the dog on the arm, and spring means cooperating with the projection to hold the projection yieldably engaged with the arm. 100 105

In testimony that we claim the foregoing as our own, we have hereto affixed our signatures in the presence of two witnesses.

ALPHONSE C. KETTERER,
GEORGE P. SLANKER.
